UNITED STATES PATENT OFFICE.

ANGELO TOLER, OF BERWIND, COLORADO.

MINER'S ELECTRIC LAMP.

1,186,454.

Specification of Letters Patent. Patented June 6, 1916.

Application filed April 24, 1915. Serial No. 23,745.

To all whom it may concern:

Be it known that I, ANGELO TOLER, formerly a subject of the Emperor of Austria-Hungary, but having declared my intention 5 to become a citizen of the United States, residing at Berwind, county of Las Animas, and State of Colorado, have invented certain new and useful Improvements in Miners' Electric Lamps; and I do declare the following 10 ing to be a full, clear, and exact description of the invention, such as will enable others skilled in the art to which it appertains to make and use the same, reference being had to the accompanying drawings, and to the 15 characters of reference marked thereon, which form a part of this specification.

My invention relates to improvements in electric lamps for miners' use and of the class in which the lamp is detachably connected with the miner's cap, while the battery for supplying the lamp is connected 20 with the waist belt.

My object is to provide a construction of this class of such character that there shall 25 be no possible chance for a spark which might ignite the coal gas or dust within the mine.

In my improved construction, the lamp proper or incandescent bulb and its screw 30 stem are mounted in a socket carried by the lamp frame, the filament members of the lamp being respectively electrically connected with contacts concealed within the base of the frame by means of a screw cover 35 which closes the chamber in the base and is locked against removal except by the employment of a special key. Hence, there is no opportunity for an exposed spark resulting from arcing at either contact with which 40 the filament of the lamp is connected. Even the miner himself cannot remove this cover, since he is not supposed to have a key which will unlock the same. The two contacts arranged within the base of the lamp frame 45 are respectively connected with electrical conductors which lead to a battery (not shown), it being assumed that the battery is carried on the person of the user. A relatively small battery which may be easily 50 carried by connecting it with the belt of the person using the lamp, will supply the latter with current for a considerable number of hours.

Having briefly outlined my improved construction, I will proceed to describe the same in detail, reference being made to the ac-

companying drawing, in which is illustrated an embodiment thereof.

In this drawing, Figure 1 is a side elevation of the lamp shown in detail. Fig. 2 is 60 a rear end view with the rear screw cover removed, being a view looking in the direction of arrow 2, Fig. 3. In this view, the lamp is shown on a larger scale than in Fig. 1. Fig. 3 is a section taken on the line 65 3-3, Fig. 2.

The same reference characters indicate the same parts in all the views.

Let the numeral 5 designate the lamp casing, which consists of a forward member 6 and a rear member 7. The member 6 is relatively large and is adapted to receive a reflector 8 whose inner extremity is apertured as shown at 9, to fit closely around the insulation 12 of the socket 10, which is threaded to receive the screw plug 13 of a relatively small incandescent lamp 14. The outer extremity 15 of the reflector is clamped between the inner face of the lens 16 and the forward extremity of the casing. The 80 holder 17 of the lens 16 is screwed upon the forward portion of the casing as shown at 18.

The rear portion 7 of the casing is reduced in size and is preferably cylindrical in 85 shape, and is exteriorly threaded to receive a screw cap 19, whose flange 20 is interiorly threaded to cooperate with the threads of the casing member. When this cap is applied, a closed compartment 21 is formed, which is 90 spaced from the forward compartment 22 in which the reflector is located, by a partition 23. This partition is covered on its rear surface by insulating material 24, which is continuous with the insulation 12 surrounding the socket 10, and also with insulation 25 which covers the interior surface of the rear portion 7 of the casing.

The base of the screw cap 19 is covered on the inside with a layer of insulating material 26 which, when the cap is screwed into place, is clamped between the base 19 and the free edge of the member 7 of the casing. Hence, the walls of the chamber 21 are practically covered with insulating material. 105 The inner extremity of the socket 10 however, is expanded to form a contact plate 27 with which a conductor 28 is connected, as shown at 29. This contact plate 27 is separated from the lamp casing by means of the 110 insulating material with which the rear surface of the partition 23 is covered. This

plate is also spaced on the inside from the rear part 7 of the casing by means of insulating material with which the latter is equipped, as heretofore explained. Also applied to the insulated surface of the partition 23, is a contact plate 30 provided with a spring arm 31, whose free extremity is engaged by the inner contact end 32 of the lamp which is insulated from the screw plug 10 in accordance with the regular construction of these lamps. This plate 30 is connected with the other conductor 35 as shown at 33. These two conductors 28 and 35 enter an opening 34 formed in the front part 6 of 15 the casing. After entering the casing compartment 22, these conductors pass through openings 36 and 37 formed in the partition 23 and enter the rear compartment 21 of the casing, where they are connected with 20 the contact plates 27 and 30. Outside of the lamp casing, the opening 34 registers with the passage 38 of a flexible tube 39 composed of closely wound spring wire. This flexible tube protects the conductors 25 where they pass through the opening 34 and obviates the possibility of injury to the insulating material as might be the case if they were allowed to engage the rough edge of the casing as the position of the lamp is 30 moved while in use. However, by the employment of this flexible tube, any exterior pull on the conductors in a lateral direction will bring them first in contact with the outer extremity of the tube, which will prevent the wearing engagement with the 35 casing.

The flange 20 of the cap 19 is provided with a threaded opening 40 which registers with a similar opening 41 formed in the 40 part 7 of the lamp casing, and the cap is normally locked against turning on the casing by means of a screw 42, which is threaded into these openings. The outer extremity of this screw is formed angular, 45 preferably square in cross section to fit a socket key 44 whose inner end is shaped to fit the outer extremity of the screw. After the cap is locked in place by the insertion of the screw, the cap cannot be unscrewed 50 or removed except by the person who holds the key. This is an important safety feature, since it will prevent the possibility of the opening of the compartment 21 of the lamp casing under circumstances which 55 might result in the exposure of a spark at either of the contact plates 27 or 30.

The cap 19 of the lamp is provided with a hook 45 adapted to be connected with the cap of the person using the lamp. The 60 flange 20 of the screw cap 19 is provided

with a sleeve 46 which extends outwardly beyond the outer extremity 43 of the screw 40, far enough to prevent tampering with the screw except by the employment of a proper socket key. 65

From the foregoing description, it will be understood that my improved lamp is so constructed that it possesses the elements of safety for miners' use, to a maximum degree. 70

Any suitable portable battery may be employed in connection with the lamp, but as this battery is a stock article and no part of my invention, I have not considered it necessary to illustrate it in the drawing. 75

Having thus described my invention, what I claim is,

1. In a miner's electric lamp comprising a casing having a partition separating its chamber into front and rear compartments, 80 contacts mounted on the partition and located in the rear compartment, said contacts being insulated from each other and from the partition, the latter having an opening in which a socket is located to receive the 85 lamp, the inner extremity of the socket merging into one of the said contacts, an incandescent lamp whose plug enters the socket and whose opposite electrode engages the other contact, and closures applied to 90 the opposite extremities of the casing, the forward closure including a transparent member.

2. A miner's lamp comprising a casing having a partition separating its chamber 95 into front and rear compartments, the said partition having an opening, a socket mounted in said opening but insulated from the partition, a reflector mounted in the front compartment and fitted around the said 100 socket, a closure for the front compartment securing the reflector in place, the said closure including a lens, contacts mounted on the partition and located in the rear compartment, electric conductors respectively 105 connected with the said contacts and passing through separate openings formed in the partition, and a single opening formed in the casing, an incandescent lamp inserted in the said socket and whose electrodes are respectively electrically connected with the said contacts, and a screw cap or cover applied to the rear extremity of the casing for securely closing the rear compartment. 110

In testimony whereof I affix my signature 115 in presence of two witnesses.

ANGELO TOLER.
